ROLLER

Application filed August 8, 1930. Serial No. 473,885.

This invention relates to machines embodying a roller for contact with the material being operated upon, and to such rollers. More particularly it relates to rollers having a contacting surface provided by a carbohydrate compound derivative, preferably a relatively non-inflammable cellulose derivative such as cellulose acetate. While the invention is not confined to the textile industry, it is, for 5 the sake of definiteness described with more particular reference to that art.

In the textile industry, in the process of preparing fiber for the spinning operation, the sliver and roving are subjected to the preparatory operation in preparatory frames whereby the material is doubled, extenuated and slightly twisted. For the accomplishing of this, the machine includes a series of fluted suitably driven metallic rollers and, above 10 the metallic rollers, a cooperating set of weighted rollers driven by frictional contact from the metallic rollers. The fibers being treated pass between the covered and the fluted rollers and, the contact points of the rollers 15 with the goods being spaced farther away in relation to each other in the direction of travel of the fiber than the average length of the fiber, a fiber is not acted upon simultaneously by two sets of rollers, and this 20 causes a sliding effect of the fibers past each other and tends to place the fibers parallel, which is the condition desired. It is the practice of the art, to use for the mentioned 25 weighted frictionally driven rollers, a roller presenting a relatively soft surface, the roller being made up of a metallic core covered with a layer of woolen cloth and, on the exterior, a layer of leather, thus to give the desired 30 soft surface.

The leather covered roller has been found in practice to have many serious objections. A leather covered roller even when new cannot be operated without a top clearer because the fibers adhere to the leather. A certain 35 amount of friction must exist between the roller and clearer to keep the roller free from fibers and foreign matter, and this friction causes the surface of the roller to become rough which makes the roller less capable of 40 performing the work satisfactorily because

the rougher the surface is, the greater is the accumulation of fiber. Therefore, a leather covered roller must frequently be varnished to keep it smooth; and before varnishing the roller must be washed, and during this process many rollers are spoiled. Also the leather cover tends to stretch and work loose on the under layer of woolen cloth (cot). Furthermore the leather is not particularly durable, and has a high initial cost, a high 55 cost for covering the roller, and a high cost of maintenance. We have devised a preparatory frame, and a roller therefor, wherein and whereby the above indicated, and various other difficulties are overcome. 60

One object of the present invention is to provide a preparatory frame having a roller of such character that difficulties of the type above indicated are eliminated. A further object is to provide a roller for use in preparatory frames, and in other machinery of comparable character, presenting various features of advantage over the rollers of the prior art. To these ends and also to improve generally on apparatus and devices of the 70 general character indicated, the invention consists in the various matters hereinafter described and claimed. 75

Without restricting the invention thereto it is described with reference to the accompanying drawing. In the drawing, Fig. 1 is a conventional elementary view of that portion of a type of preparatory frame known as fly frame or speeder comprising the driven rollers, the soft-surfaced weighted rollers, 80 and the clearer for such rollers, and embodying the present invention; Figs. 2 and 3 are longitudinal diametrical cross-sectional views of rollers embodying the present invention; and Fig. 4 is a longitudinal diametrical cross-sectional view indicating a 85 tool for, and the manner in which, the plastic covering of the present invention may be fitted over and attached to the core of the roller. 90

In general, the invention comprises a roller having a surface of a carbohydrate-compound, desirably non-inflammable, the compound desirably being a plasticized cellulose derivative, such as cellulose acetate plastic. 100

In making the roller, a suitable core, preferably a cylindrical metal shell, is covered over its entire cylindrical contacting surface with the covering compound, an intermediate layer (or layers) of cushioning material, e. g. felt, being desirably, but not necessarily, used between the core and the covering compound, the felt or the like giving a padded roller. Instead of cellulose acetate other preferably relatively non-inflammable esters of cellulose such as those made by esterification with the higher fatty acids or carbocyclic acids, may be used. Esters of other carbohydrates such as starch, may also be used; also carbohydrate ethers such as benzyl and ethyl cellulose. Suitable plasticizers and solvents should, of course, be selected to suit each case, in accordance with the teachings of the art of plasticizing carbohydrate compounds.

In consideration of the fact that relative non-inflammability is desirable, in cases where, for some particular reason, it is desired to use a compound (e. g. cellulose nitrate) below the standard of intended non-inflammability, a suitable selection of fire-proofing plasticizers and/or loading materials can, of course, be made.

Referring now to the drawing, there is illustrated in Fig. 1, in an elementary way with the driving gears etc. omitted, a fly frame 1, such as an intermediate, roving frame or jack frame. As will be understood by those skilled in the art, the same comprises the creel 2, the driven rollers 3, the speeds of which increase from left to right (in the drawing), the frictionally driven mated rollers 4, the clearer 5 of woolen cloth, and the spindle 6 with its flyer 7 and bobbin B. In operating the roving S is fed between the rollers 3 and 4 where it is doubled, extenuated and slightly twisted and finally wound onto the bobbin B. As will be understood, the rollers 3 and 4 and the clearer 5 extend crosswise of the machine, and as many sets of spindles are provided as are called for by the intended capacity of the machine. In particular accordance with the invention, the machine embodies rollers 4 of the particular character now to be described in detail.

Referring to Figs. 2 and 3 the roller 4 embodies a preferably metallic shell 8 and a covering 9, an intermediate layer or cot 10 of, say, felt being used in certain instances, as illustrated in Fig. 2. As previously mentioned the covering 9 is, in accordance with the invention, of carbohydrate compound, preferably in the form of a plastic such as cellulose acetate plastic.

The metal roller 8, with or without a cot, is covered with the plastic 9 by extruding a tube of plastic directly over the roller, the subsequent shrinkage of the tube causing the same to grasp the roller tightly; or the tube, previously formed by extrusion, or other means familiar to those skilled in the plastic

art, is softened by immersion for a sufficient period, say up to 24 hours, in a softening bath, such as a mixture of water and acetone, or water, or acetone and glycerine, or water and mono-methyl ether of ethylene glycol, or various other diluted solvents. After the plastic is thus softened it is stretched and slipped over the roller whereupon, after evaporation of the softening materials, the tube shrinks and adheres firmly to the roller. (A suitable cement may be used if desired). Thereafter the covered roller is subjected to a seasoning operation for seasoning the plastic, and finally is ground "down to the center". Other methods of covering the roller may also be used, for example plastic sheeting may be rolled about the metal shell and cemented thereto, or a thick dope of the plastic dissolved in suitable solvents may be applied by spraying, dipping or brushing.

The mentioned method, of stretching the plastic tube and slipping it over the central shell to shrink theron, may conveniently be performed with the tool illustrated in Fig. 4. Such tool, designated generally as 11, comprises the thin walled cylinder 12, preferably of metal, and the nose 13. The portion 12 is of a proper diameter and length to closely receive the shell 8 to be covered. In use, the nose 13 is inserted in the softened plastic tube 9 and the tube slid along the nose, in the meantime being stretched, until it is received on the portion 12, in register with the shell 8 with the portion 12 separating the tube and shell. The tube and shell are now simultaneously moved to the right (in Fig. 4) to free them from the tool, and the tube 9 shrinks upon the shell 8 as aforesaid. This method is also applicable in cases where the roller is first provided with a cot cemented thereon.

While rollers embodying the invention may comprise various carbohydrate compound plastics, plastic having a base of cellulose acetate, preferably of the grade ordinarily used in the manufacture of plastic, has been found particularly satisfactory, in view of its relative non-inflammability and freedom from fire hazard and other factors. As previously indicated, it is desirable to employ the compound in the form of a plastic. By way of illustration merely, and not by way of limitation, the composition may be (parts by weight) cellulose acetate 75, dibutyl phthalate 15, and dimethyl phthalate 10. In the usual way of the cellulose ester plastics art, the ingredients are macerated in a dough mixer with a suitable volatile solvent or solvent mixture, for example acetone alone or a mixture of ethyl acetate and alcohol, in suitable quantity, and after proper mixing the composition is filtered and rolled, and is pressed for slicing into sheets, or is extruded into tubes. Optionally, of course, the non-volatile ingredients may be combined with the cellulose ester in any other suitable man-

ner and the resulting mass given a desired form by heat and pressure without the presence of volatile solvent.

In place of the plasticizers, dibutyl phthalate and dimethyl phthalate, suggested above, many other plasticizers or softeners may, of course, be used, many examples of such plasticizers being described in the literature and in the patents, such for example as triphenyl 10 phosphate, triacetin, ethyl paratoluene sulfonamide, acetanilid, methyl acetanilid, ethyl acetanilide and so forth.

As will be evident, it is often preferable to vary the composition in consideration 15 of whether or not the roller is to embody a cot 10, using a softer plastic in cases where no cot is present, thus compensating for the absence of the cot. A greater degree of softness may, of course, be obtained by the use 20 of a high plasticizer content or by the addition of certain oils, e. g. castor oil, natural resins, e. g. gum elemi, or synthetic resins, e. g. certain of the glyptals or cyclic sulfonamide resins. Acetanilid and its alkyl 25 derivatives are useful for imparting softness. The above described composition of cellulose acetate 75% and plasticizers 25% may be taken as an example of a relatively hard plastic which, although it may be used in 30 rollers without a cot, is more particularly applicable to rollers including a cot. Examples of compositions yielding soft plastics, particularly useful for rollers without a cot are (parts by weight) cellulose acetate 50, triacetin 35 and diethyl phthalate 15; and cellulose acetate 50, dimethyl phthalate 40, acetanilid 10.

The thickness of the plastic on the roller 40 may be varied but, generally speaking, it has been found that a thickness of from .01 to .25 inch is desirable. Where no padding (cot) is present and a soft plastic is used the wall thickness may well be heavier than in 45 cases where the roller is padded. Thus, where no padding is used, a wall thickness in the neighborhood of .25 inch is recommended; and for a padded roller a wall thickness of .01 to .07 inch is recommended with a cot of the usual thickness. A wall thickness of .01 to .02 50 inch will give considerable cushioning whereas a wall thickness of .04 to .07 inch will give a more rigid coating. The amount of cushioning can, of course, be varied by changing the wall thickness of the plastic, since the thinner 55 the plastic wall surrounding the padding, the more evident will be the cushioning effect of the padding itself.

As an alternative in addition to the previously described methods of applying the plastic on the roller, a dope may be deposited 60 directly on the cot, or a cellulose compound varnish may be applied to the leather cover of the ordinary roller, by dipping, painting or spraying the surface.

65 Rollers of the present invention, more par-

ticularly, but not necessarily, of cellulose acetate plastic, are applicable in the manufacture of yarn from cotton, wool, silk, rayon, flax and so forth; and also in industries where at the present time rubber covered rollers are 70 used, as in the manufacture of tiles. A cellulose acetate plastic roller has the advantage of becoming smoother the longer it runs in contact with the clearer, and therefore the fiber has less tendency to adhere 75 thereto. The clearer is for the purpose of picking up any fibers or foreign matter that may be carried along with the rollers, as this is of great importance for the prevention of "roller lap"; and the mentioned smoothness 80 of the plastic roller enables the clearer to better perform its functions.

The nature of cellulose acetate plastic is such as to repel the fibers, thus preventing a "roller lap". Further, by repelling the fiber there is less accumulation of fibers and foreign matters on the clearers, hence less slugs and better yarn. Also, the plastic covered roller, unlike the leather covered roller, has no joint or seam, and also the plastic is more 85 durable than leather and the initial costs, covering costs and maintenance costs are 90 greatly reduced by the plastic.

While the invention has been described with more particular reference to a fly frame, it will be understood that it is applicable to other preparatory frames such as lap machines, combers and drawing frames; and it is also applicable to other textile machines embodying rollers for contact with the fibers, such as spinning frames.

We claim:

1. A textile-fiber-contacting roller having a contacting surface of a cellulose acetate plastic composition comprising cellulose acetate and, as a plasticizer therefor, an aromatic ester.

2. A textile-fiber-contacting roller having a contacting surface of a cellulose acetate plastic composition comprising cellulose acetate and, as a plasticizer therefor, a phthalic acid ester.

In testimony whereof we affix our signatures.

JOHANNES ALFTHAN.
